UNITED STATES PATENT OFFICE.

GEORGE JORDAN, OF CHILLIWACK, BRITISH COLUMBIA, CANADA.

JACK.

Application filed September 9, 1925. Serial No. 55,270.

The present invention relates to a jack and has for its prime object to provide a telescopic structure wherein the sections are capable of being telescoped to form a most compact structure.

The prior art contains numerous different examples of telescopic jacks wherein a plurality of sleeve-like members are threadedly and telescopically associated. My specific improvement lies in the production of a jack of this nature wherein the intermediate sections of the jack are completely receivable in the lower sections, so that the most compact folded jack structure possible results.

Another important object of the invention is to provide means novel in this art for preventing the accidental disconnection of one section in relation to the other of the jack structure.

A still further important object of the invention is to generally improve upon telescopic jacks of this nature by providing an exceedingly simple construction, one which is inexpensive to manufacture, thoroughly reliable and efficient in operation, strong, durable, not likely to easily become out of order, and otherwise well adapted to the purpose for which it is designed.

With the above and numerous other objects in view as will appear as the description proceeds, the invention resides in certain novel features of construction, and in the combination and arrangement of parts as will be hereinafter more fully described and claimed.

In the drawing:

Figure 1 is a vertical section through the jack structure extended, and

Figure 2 is a horizontal transverse section taken substantially on the line 2--2 of Figure 1 looking in the direction of the arrows.

Referring to the drawing in detail it will be seen that the jack structure is formed primarily of a plurality of sleeves telescopically associated and indicated by numerals 5, 6, and 7. The larger and bottom sleeve 5 is internally threaded, the intermediate sleeves 6 are both internally and externally threaded, and the top or smallest sleeve 7 is externally threaded, and is adapted to receive an engaging member 15. A handle 16 is mounted on the smallest section 7 and has a pawl and ratchet mechanism 17 associated therewith and with the sleeve 7. The sleeves 5 and 6 are all of the same length, and

may be completely telescoped one within the other so that the height of the resultant structure will be same as the height of each section 5 or 6.

The sections 6 are provided with ratchet notches 8 and 9 interiorly thereof, the former being at the bottom end, and the latter at the top end. The sleeve 8 is provided with a notch 9 similar to notches 9 in the sleeves 6. On the lower ends of sleeves 6 and 7 there is mounted in notches 11, spring 12 provided with heads 13 normally projected out of the notches 11 and adapted to engage in the ratchet notches 8 and 9. It is to be noted that the stop ends of the ratchet notches 8 and 9 are oppositely disposed as is apparent from Figure 2.

It will be seen that when the jack is contracted, the sections 6 are completely received within the section 5, and the section 7 is almost wholly received within the smallest section 6. The jack, therefore, is very small and may be placed under an object only a short distance from the ground and therefore, is particularly useful where the wheels of an automobile or the like are sunk in the mud. By turning the handle 16, to unthread the sections in relation to each other, it will be seen that the jack may be extended. It is not possible to anticipate which of the sections will be extended first, but this is immaterial, as soon as one section is fully extended in relation to the next adjacent section, the spring thereof forces the head 13 in the notch 9, thereby preventing movement of these sections in relation to each other and causing other sections to extend in relation to each other. The spring 12, and the bottom notches 8 prevent the sections from going further than their fully collapsed position. It is preferable to provide a base plate 19 on the lower edge of the section 5, and this base plate is held in position by means of the fastening elements 20.

It is thought that the construction, operation, and utility of this improved and simple jack structure will now be clearly understood without a more detailed description by those skilled in the art.

The present embodiment of the invention has been disclosed in detail merely by way of example since in actual practice it attains the features of advantage enumerated as desirable in the statement of the invention and the above description. It will be apparent that numerous changes in the details

of construction, and in the combination and arrangement of parts may be resorted to without departing from the spirit or scope of the invention as hereinafter claimed or sacrificing any of its advantages.

Having thus described the invention, what I claim as new is:—

1. A jack structure of the class described including a plurality of threadedly and telescopicly associated sleeves, said sleeves provided interiorly with ratchet notches one at the top and one at the bottom, the notches of each sleeve being oppositely disposed, and spring pawls on the exterior of the sleeves engageable in said notches to limit the movement of the sleeves in respect to one another.

2. A jack structure of the class described including a plurality of threadedly and telescopicly associated sleeves, said sleeves provided interiorly with ratchet notches one at the top and one at the bottom, the notches of each sleeve being oppositely disposed, and

spring pawls on the exterior of the sleeves engageable in said notches to limit the movement of the sleeves in respect to one another, a handle, and a pawl and ratchet mechanism associated with the handle and the smallest sleeve.

3. A jack structure of the class described including a plurality of threadedly and telescopicly associated sleeves, said sleeves provided interiorly with ratchet notches one at the top and one at the bottom, the notches of each sleeve being oppositely disposed, and spring pawls on the exterior of the sleeves engageable in said notches to limit the movement of the sleeves in respect to one another, a handle, and a pawl and ratchet mechanism associated with the handle and the smallest sleeve, a base plate attached to the bottom edge of the largest sleeve.

In testimony whereof I affix my signature.

GEORGE JORDAN.
